UNITED STATES PATENT OFFICE.

WARREN S. JOHNSON, OF MILWAUKEE, WISCONSIN.

STEAM-GENERATOR.

No. 854,649.

Specification of Letters Patent.

Patented May 21, 1907.

Application filed August 16, 1905. Serial No. 274,389.

To all whom it may concern:

Be it known that I, WARREN S. JOHNSON, a citizen of the United States, residing at Milwaukee, in the county of Milwaukee and State of Wisconsin, have invented certain new and useful Improvements in Steam-Generators, of which the following is a specification.

My present invention relates to devices for generating steam for power purposes, and pertains more particularly to appliances for supplying water for the generation of steam and the regulation of the fire which heats the water, both of which are governed in such a manner that the amount of water furnished shall be just sufficient for the strength of the fire.

My invention is particularly applicable to the generation of steam for automobiles when liquid fuel is used.

In the accompanying drawings: Figure 1 is a side elevation of the apparatus, the generator being shown in section and portions of the boiler-casing being broken away; Fig. 2 a longitudinal vertical sectional view of the boiler and the controlling valves therefor by which the amount of water which passes into the boiler may be regulated and determined; and Fig. 3 a horizontal sectional view, taken 30 on the line 3—3 of Fig. 1, portions being broken away to more clearly show the parts which lie below the burner.

The object of the invention is to provide means for maintaining a given or stated degree of pressure at all times at the outlet of the boiler or generator. This object is attained by automatically regulating the amount of heat applied to the generator and also by regulating the quantity of water and the time at which the water may be introduced into the boiler or generator.

In the drawings A designates a steam generator of the flash or semi-flash type which by preference I employ in connection with the present invention, though any other form of generator may be used. Said generator is composed of a number of coils connected in series so as to form a continuous passage for the water and steam therethrough from the water-inlet B to the steam outlet C. Inasmuch as the boiler forms no part of the present invention, it is not herein shown in detail.

The boiler is surrounded by a shell or casing D, provided with a flue E. 55

F denotes a pipe leading from the source of liquid fuel, the fuel passing into said pipe under a pressure of, say for instance, 70 pounds per square inch. Pipe F communicates with a second pipe G through a governor H, said 60 governor being so arranged as to cut off or materially reduce the communication between the pipes F and G when the pressure within the boiler reaches a predetermined maximum, say, a pressure of 225 pounds. 65

The governor is connected with the steam-space of the boiler by a pipe I, a pressure-gage J also communicating with the pipe. The governor is adjustable, and by observing the gage J the governor may be set to prevent the flow of fuel at any desired steam pressure. 70

Any form of governor may be employed and as the construction of the governor forms no part of the present invention it is not 75 herein shown in detail.

The pipe G is connected to a flanged coupling K, which in turn is bolted to the flanged end L of a retort or chamber M, the inner end of which is closed by a removable plug N. 80

A pipe O is secured to the inner face of the flanged coupling member K and extends inwardly through the retort M to a point adjacent to the plug N. The liquid fuel which passes from the pipe G must traverse pipe O 85 before it can be discharged into the retort M, and in passing through said pipe it becomes heated and partially vaporized. The fuel is, therefore, in condition to be completely vaporized or gasified by the retort M as it 90 leaves the end of the pipe O, whereas, if the fuel used were a heavy hydrocarbon it would be decomposed if it came in contact with the retort M in a cold state.

The vaporized fuel passes from the retort M through a pipe or lateral extension P, located at one end of the retort outside of the casing of the boiler. Said pipe carries a nozzle Q which stands in alignment with an air-mixing pipe or chamber R, the inner end of which is in communication with a manifold S. The manifold has connected to it and extending outward from each side thereof a series of perforated pipes T, the outer ends of which are connected to manifolds U. This 105 burner underlies the retort and when once

lighted serves to vaporize the fuel which passes therethrough under pressure.

The gas which passes from the nozzle Q will, of course, entrain the proper amount of air as it enters the mixing-pipe or chamber R, so that the burner is in effect a Bunsen burner and complete combustion is had.

No claim is herein made to this form of burner, and the subject-matter thereof is reserved for a future application to be filed by me.

From the description thus far given it will be seen that the burner is automatically regulated and that when the steam pressure within the boiler approximates 225 pounds the supply of fuel will be materially reduced. When the pressure reaches the maximum point fuel will be entirely cut off, so that the further generation of steam will be prevented.

To start the burner a torch is applied to the pipe P and the fuel then turned on, or a pilot burner may be employed, as is usual in apparatus of the kind referred to herein.

Water, as required, is fed into the boiler by a pump, the flow of the water to the boiler and the amount which may pass therein being controlled by the pressure of the fuel which enters the burner, and inasmuch as the pressure of the fuel is directly regulated by

the pressure within the boiler, water will be fed into the boiler at such times only as it may be required. In other words, the mechanism is such that flooding of the boiler is prevented.

V denotes the pipe leading from the water tank or other source of supply, the pipe connecting with a pipe W, which in turn is connected to a pump-head X below the inlet valve Y thereof. A second valve, Z, is mounted in the pump-head, the two valves Y and Z acting in conjunction with a piston A' to draw the water from the pipe V and force it from the pump-head into a pipe B' which is connected to the pump-head at one end. The opposite end of said pipe B' is connected to a by-pass shell or casing C', said shell or casing communicating through a pipe D' and an adjustable valve E' with the water inlet B of the generator. A pipe F' communicates with the lower portion of the by-pass shell or casing C' and also with the pipes V and W. A by-pass valve G' is mounted in the shell or casing C' and serves, under certain conditions, to close the passage through said casing from the pipes B' to F'.

The valve is carried upon a stem H', which works through a stuffing-box I', the lower end of the stem being connected to a diaphragm J' which forms the movable member of a fluid-pressure motor K'. A spring L' surrounds the stem and serves to move the diaphragm downwardly and thereby to withdraw the by-pass valve G' from its seat when the motor is relieved of pressure from within.

The chamber of the motor K' is in commun-

ication with the source of fluid supply at a point between the governor H and the burner, through a pipe M', and by reason of such connection the diaphragm is at all times subject to the pressure of the fuel which passes into the generator of the burner. So long as the pressure of the fuel is sufficient to overcome the action of the spring L' (which latter is quite light) the valve G' will be held to its seat, and the by-pass between pipes B' and F' will remain closed.

A second by-pass N' connects the pipes B' and W, an adjustable by-pass valve O' being mounted in said passage and serving normally to keep the passage closed. The valve is provided with a stem P' which extends outwardly through a nut Q', the inner end of which bears against one end of a coiled spring R', that encircles the stem and bears at its opposite end against the valve O'. By adjusting the nut the tension of the spring may be varied and the valve thus held to its seat until a certain pressure is exceeded. A cap S' covers the nut and prevents leakage there-through.

The valve O' may be set to open at any pressure which may, for the purposes of the present description, be assumed to be 300 pounds per square inch.

In practice valve E' is adjusted so as to afford a certain restricted opening, which will allow the passage of the proper amount of water when it is being forced therethrough at a given pressure by the pump, the regulation of the valve being such that the amount of water which can enter the generator during a given period is exactly that which the fire can evaporate in a given time.

The operation of the apparatus is as follows: Assuming that the proper quantity of water has been fed into the generator, a small amount of fuel is allowed to enter the retort M and the pipe P is then primed. The vaporized fuel issues from the nozzle under pressure and, passing through the mixing pipe R, will issue from the burner, where it is lighted. The fuel is then turned on and, by the action of the burner will continue to be vaporized.

The flow of fuel will continue until the steam pressure approximates 225 pounds, at which time the governor H comes into action, it serving to reduce or entirely cut off the supply when the maximum pressure is reached. As long as the fuel pressure is maintained in pipes G and M' the diaphragm I' of the motor K' will remain elevated and the by-pass valve G' will be closed; but as the pressure is lowered or cut off by the action of the governor H the diaphragm will move downwardly and withdraw valve G' from its seat, thereby opening the by-pass C' and allowing the water to circulate back to the pump-piston and thus preventing its being forced through the restricted opening.

formed by the valve E' into the generator. It will thus be seen that the flow of water into the boiler is stopped or cut down as the fire is lowered in consequence of the rise in steam pressure in the generator.

It is necessary that even when the water is entering the generator a definite amount should be supplied, as otherwise the generator will receive too small or too large a quantity thereof. To provide for the passage of the proper supply of water, I adjust the valve E' to such a point that the amount of water which can enter the generator is exactly that which the fire can evaporate. To accomplish this proper feeding through the restricted opening, it is essential that the governor H should be set to operate at a pressure less than that at which the by-pass valve or water-pressure controlling valve O' is set, as, in the present instance, at 225 pounds and 300 pounds, respectively, which gives a constant difference of pressure of 75 pounds per square inch. This difference will permit the pump to force as much water through the restricted opening (formed by valve E') into the generator in a given time as would pass through the same sized opening in the same time at 75 pounds pressure to the atmosphere.

With a burner adjusted to evaporate ten pounds of water per minute the valve E' is so adjusted as to allow just ten pounds to pass into the generator in that period of time. As a consequence, there can be no flooding of the boiler, a serious matter in a boiler of the flash type, and particularly so in those in which the water is fed into the uppermost portion and prevented from gravitating to the lowermost portion or coils from which the superheated steam is withdrawn for use.

With the fuel supply regulated according to the demands of the generator, the by-pass valve G' opening and closing in response to the raising and lowering of the fuel pressure in the gas generator, and the water pressure controlling valve regulated to control the action of the pump it is evident that the generator will give a constant steam supply at an approximately constant pressure and temperature.

While I have set forth many of the portions of the apparatus in detail it is evident that they can be modified without departing from the spirit of the invention. For instance, any means may be employed for securing an adjustable restricted opening between the pump and the generator; so, too, any form of motor may be employed for actuating the by-pass valve G' in response to the rise and fall of pressure within the fluid supply pipe.

Having thus described my invention, what I claim is:

1. In combination with a steam generator; a burner; a source of liquid fuel under pres-

sure leading to the burner; a governor for controlling the passage of the fuel to the burner, said governor being actuated by the pressure within the generator; a pump for forcing water into the generator; a fluid-pressure motor in communication with the fuel supply at a point between the governor and the burner; and a by-pass valve for the pump actuated by said motor.

2. In combination with a steam generator; a burner controllable by the steam pressure within the generator; means for controlling the supply of water to the generator; and controlling means for said supplying means, said controlling means being under the direct influence of the pressure of the fuel passing to the burner.

3. In combination with a steam generator; a water supply communicating therewith through a restricted opening; a pump for forcing water through said opening; an adjustable relief valve; and a by-pass valve for the pump responsive to and actuated indirectly by variations in the generator pressure.

4. In combination with a steam generator; a water supply communicating therewith through a restricted opening; a pump for forcing water therethrough; an adjustable relief valve for the pump; a by-pass valve for the pump; a fluid motor for actuating said by-pass valve; and a pipe connecting said motor and the source of fuel supply.

5. In combination with a steam generator; a burner; a source of fuel supply connected to said burner and adapted to deliver the fuel thereto under pressure; a governor interposed in the connection between the burner and source of fuel supply and serving to cut off the supply when the pressure within the generator has reached a predetermined point; a connection between said generator and the governor; a water-inlet to the generator, said inlet being provided with an adjustable restricted opening; a pump; a by-pass valve for said pump; a fluid-pressure motor serving to actuate said valve; connections between said motor and the source of fuel supply, said connections being made at a point between the governor and the burner; and an adjustable relief valve for the pump.

6. In combination with a steam generator; a burner; a pipe connected to said burner and adapted to deliver fuel thereto under pressure; a governor controlling the passage of fuel through said pipe; connections between said governor and the steam-space of the boiler; a pump adapted and designed to deliver water to the generator through an adjustable, restricted opening; a by-pass valve for the pump; a fluid-pressure motor connected to said valve; connections between said motor and the pipe for supplying fuel to the burner, said connections being made at a point between the burner and the governor;

and means for regulating the degree of pressure to be exerted by the pump in forcing the water through the restricted opening.

7. In combination with a steam generator; 5 a burner acting primarily upon the steam-containing coils of the generator, said burner being controlled by the steam-pressure within the generator; means for forcing water into the upper portion of the generator 10 through an adjustable restricted opening; and means controlled by the pressure of the

fuel passing to the burner for regulating the amount of water which may be forced through the restricted opening.

In testimony whereof I have signed my 15 name to this specification in the presence of two subscribing witnesses.

WARREN S. JOHNSON.
